Primary Examiner — Lauren R Calve*(74) Attorney, Agent, or Firm* — Notaro, Michalos & Zaccaria P.C.(57) **CLAIM**

The ornamental design for a tie and socks holder, as shown and described.

DESCRIPTION

FIG. 1 is a front elevational view of a tie and socks holder in an unfolded configuration showing my new design; FIG. 2 is a front elevational view of FIG. 1 in a folded configuration and in environmental use; FIG. 3 is a rear elevational view thereof; FIG. 4 is a right side elevational view thereof; FIG. 5 is a left side elevational view thereof; FIG. 6 is a top plan view thereof; and, FIG. 7 is a bottom plan view thereof.

The short dash-long dash lines in the figures represent environmental subject matter and form no part of the claimed design.
